UNITED STATES PATENT OFFICE

2,613,601

INK FOUNTAIN AGITATOR

Spencer D. Forbes, Seattle, Wash.

Application August 15, 1950, Serial No. 179,450

5 Claims. (Cl. 101—364)

1

This invention relates to ink fountains as employed in printing machines, and particularly as used in printing machines known as "offset duplicators" and machines of a like kind. More specifically stated, the invention pertains to improvements in ink agitators, as used in ink fountains, and in the agitator operating or actuating means.

It is the principal object of the present invention to provide an agitator for use in ink fountains to insure that the ink will be applied evenly and constantly to the ink fountain roller, thus to maintain an even film of ink on the printing plates and to insure uniformity of density in the printed material.

It is also an object of the present invention to provide a simple and relatively inexpensive agitator, for use in ink fountains, that may be easily and readily applied to ink fountains as they already exist, and which can be quickly and easily detached for cleaning when this is desired.

Further objects of the invention reside in the details of construction and combination of parts, and in their mode of application to a fountain and in their use, as will hereinafter be fully described.

In accomplishing the above mentioned and other objects of the invention, I have provided the improved details of construction, the preferred forms of which are illustrated in the accompanying drawings, wherein—

Fig. 1 is a plan, or top view, of an ink fountain that is equipped with agitator and agitator driving mechanism embodied by the present invention.

Fig. 2 is a vertical section through the fountain and agitator plate, taken on line 2—2 in Fig. 1.

Fig. 3 is an enlarged, perspective view of one of the ink distributing fingers of the agitator plate.

Fig. 4 is an elevation of the agitator driving mechanism, as seen from the left hand end of Fig. 1.

Fig. 5 is an enlarged vertical section taken on the line 5—5 in Fig. 1.

Referring more in detail to the drawings—

In Figs. 1 and 4, I have shown those parts of a typical printing machine known as an "offset duplicator," with which the present mechanism is directly associated. In these views 10 and 11 designate parts of the frame structure between which inking, or ink transfer rollers 12 and 13 are mounted in rolling contact, and to which ink is directly or indirectly supplied from a fountain roller 14 in the usual manner. The roller 14 is

2

revolvably supported between opposite end walls 15—15 of a housing or frame structure which includes a transverse angle bar 16 that joins the said end walls in spaced relationship. As observed in Fig. 2, the angle bar 16 is parallel with roller 14 and is spaced therefrom.

Disposed flatly against the beveled top surface of the vertical flange of the angle bar 16, is a thin flexible metal plate 20 that extends downwardly and below the roller 14, substantially into tangential relationship thereto. This downwardly inclined plate, and the roller 14 coact to form a trough in which the supply of ink is held for feeding to the rollers and plates of the machine. In Fig. 2, the ink is designated at 21, and it generally is of a semi-fluid nature and must be constantly advanced or pressed toward the roller 14. The plate 20 is secured in place by an overlying clamp plate 22. This is secured by a plurality of screws, as at 23 in Fig. 1, that are passed through the plate and threaded into the bar 16.

The amount of ink fed to the roller 14, which is rotatably driven in a direction as indicated by the arrow adjacent thereto in Fig. 2, is regulated by the accurate spacing of plate 20 from the roller surface. If left free, the plate will assume a definite spaced relationship from the roller to provide for the application of a film of ink of maximum thickness. To decrease the film thickness, the plate is sprung toward the roller, and this adjustment is effected by means of a plurality of adjusting screws 24 that are threaded horizontally through the bar 16, to contact with the under surface of the lower edge portion of the plate at spaced intervals therealong.

The means for driving the various rollers, including roller 14, may be of any suitable kind, and forms no part of the present invention.

The agitator embodying the present invention is applied to the above standard parts of the machine without requiring change or alteration of their design and mode of use.

In its present preferred form of construction the agitator comprises a flat, elongated metal plate 25 that is disposed along and flatly upon the top surface of the clamp plate 22. At its lower edge, the plate 25 is formed at regularly spaced intervals therealong, with fingers or prongs 26 that extend into the ink supply and into close proximity to the adjacent face of roller 14. It will be observed by reference to Fig. 2 that the fingers are somewhat downwardly curved and extend closely along the top surface of the plate 25. The ends of the fingers 26 are formed with beveled points, providing flat, diverging sur-

faces, as designated at 27 and 28 in Fig. 3, whereby, under back and forth reciprocal action of the plate, the ink is pressed toward and against the adjacent face of the roller 14.

The agitator plate 25 is guided in its reciprocal travel by means of the heads of two of the plate securing screws 23. These heads, designated at 23', are substantially spaced apart and are contained in longitudinal slots 30 formed in opposite end portions of the plate 22. Coacting with the guide screws, is a spring pressed latch 31 mounted in a housing 32 that is fixed on the under side of a central, top edge extension or flange 33 formed on the agitator plate. The toe of the latch is extended beneath the longitudinal top edge of the clamp bar 22, as noted in Fig. 2, to keep the agitator plate in proper position, but without interfering with its reciprocal action.

To effect the reciprocation of the agitator plate, I provide the following mechanism:

Rotatably mounted on the horizontal top surface of the frame member 10, at one end of the fountain, is a ratchet wheel 40. This is rotatable about a pivot screw 41, passed therethrough and secured in member 10. The wheel is connected by means of a link 52 with the adjacent end of the agitator plate 22, so that the plate is reciprocally moved with the rotations of the ratchet wheel.

The ratchet wheel 40 is intermittently rotatably advanced by means of a pawl 44 mounted on an arm 45 that, in turn, is mounted to oscillate on the pivot screw 41. The arm 45 is oscillated by means of a connecting link 46, which has one end pivotally connected with the outer end of the arm, as at 47, and its other end pivotally connected as at 48, with an oscillating part of the driving mechanism of the machine, which is shown in Fig. 4 to be an arm 58, oscillated by a link 51 which is connected eccentrically to a rotating gear wheel 52.

It will be understood, by reference to Fig. 1, that as the arm 45 is actuated in one direction, the pawl 44 mounted thereon will cause a rotatable advancement of gear wheel 40, and this movement, through the link 42, will cause an endwise movement of the agitator plate 22. Repeated advance movements of the gear will result in a back and forth reciprocal action of the plate, by intermittent movements, that insures constant agitation of the ink and its forced application or flow to the surface of the fountain roller 14.

Adequate agitation of ink is effected by the fingers 26 of the plate, and these are spaced apart a distance that is less than the extent of reciprocal movement in opposite directions so that no part of the ink supply will be left undisturbed. The beveled end surfaces 27 of the fingers 26 operate to force the ink toward the roller surface.

To remove the plate 32 for cleaning, it is only required that the latch 31 be released from the top edge of plate 22, then the plate can be lifted free of the fountain.

The parts are of simplified construction, easy to apply or remove and when operated as described, maintain satisfactory flow of ink to the roller 14 and an even application to the printing plate.

Having thus described my invention, what I claim as new therein and desire to secure by Letters Patent, is:

1. In a printing machine, the combination with an ink fountain including a fountain roller, a

wall spaced therefrom and a bottom plate fixed on said wall and coacting with the roller to form a trough for a supply of ink, and a bar fixed to and extending along the top edge of the trough parallel with the roller; or an agitator plate extended along and reciprocally mounted on said bar, means on the bar for guiding the plate in its reciprocal action, a latch means on the plate normally engaging the bar to retain the plate in its functional position and releasable from the bar for removal of the plate from the trough, and means operable by a driven part of the machine for reciprocally actuating the agitator plate; said agitator plate being formed along one edge thereof with a plurality of spaced and downwardly extending fingers for the agitation of ink contained in the fountain, terminating close to the surface of the roller in points with oppositely beveled surfaces whereby ink is caused to be pressed against the roller surface by the reciprocal action of the agitator plate.

2. In a printing machine, the combination with an ink fountain including a fountain roller, a wall in parallel, spaced relationship thereto, and a bottom plate supported upon said wall and extended in a downwardly inclined position therefrom into cooperating relationship with the roller to provide a trough for the retaining of a supply of ink; of a clamp bar holdingly applied flatly against said bottom plate, with its upper longitudinal edge extended above the wall, attaching screws applied through the bar and plate into the said wall, and having projecting heads, an ink agitator plate applied along and flatly against the said clamp bar, for reciprocal action thereon, and means operable by a driven part of the machine for effecting the reciprocal action of the agitator plate; said agitator plate having longitudinal slots formed therein along its opposite end portions containing the heads of the clamp bar securing screws therein as guides for the plate, and a releasable, spring pressed latch applied to the under side of the agitator plate and extended beneath the longitudinal upper edge of the clamp bar to retain the agitator plate in functional position.

3. A combination as recited in claim 2 wherein the agitator plate is provided along its lower edge with fingers extending into the ink and terminating adjacent the fountain roller in oppositely facing beveled end surfaces.

4. A combination as recited in claim 2 wherein the agitator plate is provided along its lower edge with fingers extending into the ink and terminating adjacent the fountain roller in oppositely facing beveled end surfaces, and said plate reciprocating means comprising a rotatably mounted ratchet wheel, a link pivotally connected at its opposite ends to the agitator plate and eccentrically to the ratchet wheel, an arm mounted for oscillating action, a pawl on said arm engageable with the ratchet wheel to effect its actuation incident to oscillation of the arm, and a link connecting the arm with an oscillating part of the machine to effect the oscillation of said arm and an intermittent rotative advancement of the ratchet wheel.

5. In a printing machine, the combination with an ink fountain including a fountain roller, and wall spaced therefrom, a bottom plate fixed on said wall and coacting with the roller to form a trough for a supply of ink and a bar that is fixed relative to extend along the said bottom plate parallel to the roller; of an agitator plate

reciprocally mounted on said bar and formed along one edge thereof with ink agitating fingers extended into the trough and having a releasable latch at its other edge normally slidably and holdingly engaged with said bar to retain it in 5 functional position, and said latch being releasable for quick removal of the agitator plate from the trough, and means for reciprocating the agitator plate.
